Term of patent 14 years

Int. Cl. D10—09

U.S. Cl. D52—7

FIG 1

FIG 2

FIG 4

FIG 3

FIG. 1 is a front view of a condition responsive device embodying the new design;

FIG. 2 is a top plan view of the device;

FIG. 3 is a side view as seen from the left side of the device shown in FIG. 1, the right side being substantially a mirror image thereof; and

FIG. 4 is a fragmentary cross-sectional view taken generally along line 4—4 of FIG. 1.

The back and bottom of the device are essentially plain.

I claim:

The ornamental design for a condition responsive device, substantially as shown and described.
